UNITED STATES PATENT OFFICE.

FRANK C. HANEY, OF DAYTON, OHIO.

TRAIN-STOP.

1,372,504.

Specification of Letters Patent. Patented Mar. 22, 1921.

Application filed August 3, 1920. Serial No. 400,929.

To all whom it may concern:

Be it known that I, FRANK C. HANEY, a citizen of the United States, residing at Dayton, in the county of Montgomery and State of Ohio, have invented new and useful Improvements in Train-Stops, of which the following is a specification.

This invention relates to automatically operated speed regulating and stopping devices for railroad trains.

An object of the invention is the provision of a device which is adjustable to prevent the speed of a train from exceeding a predetermined limit and for stopping a train in the event of a signal being set at danger.

Another object is the provision of a device which is carried by the locomotive for regulating the throttle valve and the air valve, the said device being operated by a track device which is capable of adjustment to determine the limit of speed and to operate the valve of the air brake.

Other objects and advantages of the invention will appear as the following description is read in connection with the accompanying drawings.

In the drawings:

Figure 1 is a front elevation of a locomotive with the invention applied, parts being broken away and others removed to more clearly show the invention.

Fig. 2 is a rear elevation of the invention with parts of a locomotive shown by dotted lines to illustrate its location.

Fig. 3 is a side elevation of Fig. 1.

Fig. 4 is an enlarged section on the line 4—4 of Fig. 2.

Fig. 5 is a side elevation of a brake device used in connection with the invention, the view looking at the outside of the brake.

Fig. 6 is a view similar to Fig. 5 and looking at the device from the opposite side, or the inside of the brake, one end of the device being elevated.

Fig. 7 is a plan view of the brake device.

Fig. 8 is an enlarged sectional view on the line 8—8 of Fig. 6.

Referring to the drawings in detail, wherein like characters of reference denote corresponding parts, the invention includes a locomotive carried device which is designated in its entirety by the reference character 10 and a track device which is shown at 11 and used for the operation of the locomotive carried device.

The locomotive device 10 comprises a gov-

ernor 12 which is herein shown as of the centrifugal type and which is mounted for operation upon a vertically disposed shaft 13, mounted in suitable bearings 14 and 15 provided in or carried by the locomotive frame. The shaft 13 has secured upon one end a gear 16, which is driven by a pinion 17, the latter being mounted upon one end of a shaft 18. This shaft is rotatable in bearings 19 carried by the locomotive frame and has connected thereto a flexible shaft 20, which is geared to and driven by one of the locomotive axles 21 by the gearing 22. This is only one of the many ways which may be employed for operating the governor shaft 13 and it is understood that any other suitable operating means may be employed.

The arms of the governor have pivotally connected thereto, a member 23, which is slidable on the shaft 13, when the governor is actuated and pivotally secured to this member as is shown by 24, is one end of the lever 25. This lever is pivotally mounted upon a bracket 26, and its end which is connected to the member 23 is held normally depressed by means of a spring 27, while the opposite end of this lever has connected thereto one end of a rod 28. This rod extends upwardly through the locomotive frame and is provided with a rack 29, for engagement with a pinion 30, the latter also engaging rack teeth 31 formed upon a horizontally movable rod 32. This last mentioned rod is connected with a valve 33, which is included in the steam line 34 of the locomotive for the purpose of controlling the steam to the engine, so that when the governor is actuated to move the member 23 upon the shaft, the rod 38 will operate the pinion 30 and through the rod 32 will close the valve in a degree proportionate to the movement of the member 23.

For the purpose of holding the member 23 in its lower position against the action of the spring 27, and to maintain the valve 33 in open position, there is provided a wedge shaped member 35 and slidably connected to this member is one end of a link 36 which passes upward through the lever 25 and spring 27 and has its upper end engaging the upper end of the spring. The lower end of the link 36 is arranged for operative engagement with the inclined under surface of the wedge shaped member 35 so that when the latter is moved horizontally in a direction away from the governor shaft 13,

the tension on the spring 27 is released and the member 23 permitted to slide upon the shaft 13.

The wedge shaped member 35 is connected to one end of a rod 39 which is slidable in bearings 40 secured to the frame of the locomotive. The opposite end of this rod is provided with teeth 41 which are engaged by a pinion 42, mounted upon a shaft 43 disposed transversely of the locomotive. This shaft also has secured thereon a gear 44 which is engaged by a worm 45, the latter being mounted upon a shaft 49 arranged longitudinally disposed shaft 46. Secured to the opposite end of this last mentioned shaft is a gear 47, which engages a worm 48, the latter being mounted upon a shaft 49 arranged transversely of the locomotive and rotatable in bearings 50. The shaft 49 is located in advance of the steam cylinders 51 of the locomotive and is also mounted in bearings 52 which are carried by brackets 53. These brackets also provide bearings in which are slidably mounted vertically movable rack bars 54, one of these bars being located upon opposite sides of the locomotive. The teeth of the bars 54 engage pinions 55 secured with each end of the shaft 49, so that the vertical movement rack bars 54 will rotate the shaft 49 and through the gears 47 and 48 will operate the shaft 46 so as to impart a sliding movement to the rod 39 through the gears 42 and 44 and 45. The lower ends of each of the rack bars 54 have secured thereto outwardly and laterally projecting rollers 56.

The track device 11 which is designed to be engaged by the rollers 56 for imparting a vertical movement to the rack bars 54 may be located at suitable points along the track, for example at the end of a signal block for the purpose of operating the locomotive carried device to stop the train in the event of the signal being set at danger, or the said track device may be located in advance of a dangerous curve, bridge, or railroad crossing to control the speed of the train at these points.

This track device which may be located upon one or both sides of a track, includes an adjustable controlling member 57. This member comprises spaced parallel bars 58 which are connected throughout their lengths by spaced transversely arranged substantially U shaped members 59. The bars 58 have their opposed faces beveled as shown at 60 so as to provide a flared mouth for the entrance of one of the rollers 56. When the adjustable controlling bar is in the position shown in Fig. 5, the roller 56 will pass between the bars 58 without imparting movement to the rack bar 54, the height of the bar 57 being such as to permit of this passage. However, when the bar 57 is in the position shown in Fig. 6 the roller

56 will enter the lower end of the said member, passing between the bars 58, being gradually elevated until it passes out at the opposite end of the member, the degree to which the controlling member is elevated determining the degree of operation of the steam valve as previously described. For the purpose of adjusting the controlling member 57, there is pivotally connected to each end of the said member, one end of a link 61. The opposite end of this link is pivotally connected to one arm of a bell crank lever 62, whose opposite arm is connected to one end of a rod 63. The latter is in turn connected to a rack bar 64, which is engaged by a pinion 65 mounted upon the shaft of the motor 56. This motor is preferably of the electric type and its operation may be controlled by any desired means, for example its circuit may be closed by the operation of a block signal when the latter is set at danger. In the event of the track device being positioned at points remote from a track or other signal, the circuit may be manually closed to regulate the position of the member 57 so that the speed of the train will be automatically controlled in a uniform manner each time the train passes the trace device.

The bell crank levers 62 are mounted in suitable bearings 63 secured to the track ties and also supported upon these ties are guides 64 for the purpose of holding the member 67 in position.

It is believed that when the foregoing description is read in connection with the accompanying drawings, the construction, proportions and advantages of the invention will be apparent. The right is herein reserved to make such changes as properly fall within the scope of the appended claims.

Having described the invention what is claimed is:—

1. A train controlling device embodying a governor, means for operatively connecting the governor with an axle of a locomotive, means including a pivotally mounted spring actuated lever connected to the governor for holding the latter in an inactive position, a valve included in the steam line of the locomotive for controlling its operation, means connecting the governor and valve for operating the latter when the governor holding means is released and a track device for releasing the governor holding means.

2. A train controlling device embodying a governor, means for operatively connecting the governor with an axle of a locomotive, means including a longitudinally slidable wedge shaped element for holding the governor in an inactive position, a valve included in the steam line of the locomotive for controlling its operation, means connecting the governor and valve for operating the latter when the governor holding means is released and a track device for releasing the governor holding means.

ing the latter when the governor holding means is released and a track device for releasing the governor holding means.

3. A train controlling device embodying a governor, means for operatively connecting the governor with an axle of a locomotive, means for holding the governor in an inactive position, a valve included in the steam line of a locomotive for controlling its operation, means connecting the governor and valve for operating the latter when the governor holding means is released, a transversely arranged shaft operatively connected to the governor releasing means, a vertically movable shaft operatively connected to the transverse shaft and a track device for operating the vertically movable shaft.

4. A train controlling device embodying a governor, means for operatively connecting the governor with an axle of a locomotive, means for holding the governor in an inactive position, a valve included in the steam line of the locomotive for controlling its operation, means connecting the gover-

nor and valve for operating the latter when the governor holding means is released, a transversely arranged shaft operatively connected to the governor releasing means, a vertically movable shaft operatively connected to the transverse shaft, a track device for operating the vertically movable shaft and means included in the track device for regulating the degree of movement of the vertically movable shaft. 30

5. The combination with a train controlling mechanism having means for controlling the operation of the throttle and means extending from the locomotive for operating the throttle controlling means, of a track device located adjacent the track in the path of the extending means for moving the latter to operate the throttle controlling means and means whereby the track device may be adjusted to regulate the degree of such movement to control the speed of the train. 40

In testimony whereof I have affixed my signature.

FRANK C. HANEY.
